UNITED STATES PATENT OFFICE.

BENJAMIN F. McCREARY, OF NEW YORK, N. Y.

MEANS FOR CARRYING LIFE-LINES.

1,072,968.

Specification of Letters Patent. Patented Sept. 9, 1913.

Application filed September 21, 1912. Serial No. 721,641.

To all whom it may concern:

Be it known that I, BENJAMIN F. McCREARY, a citizen of the United States, and a resident of the city of New York, 5 Jamaica, borough of Queens, in the county of Queens and State of New York, have invented a new and Improved Means for Carrying Life-Lines, of which the following is a full, clear, and exact description.

10 The invention relates to life-saving apparatus used for carrying a life line from shore to ship and vice versa, or to a high building or other structure.

The object of the invention is to provide 15 a new and improved means for carrying life lines and arranged to prevent the projectile carrying the life line from tumbling over during its flight and to cause the projectile to travel a great distance.

20 For the purpose mentioned use is made of a projectile in the base end of which is centrally anchored one end of a wire cord or cable extending through a groove formed lengthwise in the peripheral face of the projectile, and a line attached to the free end 25 of the said wire cord or cable. Use is also made of a projectile provided with a recess for the reception of a life line anchored a one end in the bottom of the recess, the 30 other end of the line terminating in a ring resting against the base of the projectile, and engaging means for catching the ring at the time the projectile is fired out of a gun or mortar.

35 A practical embodiment of the invention is represented in the accompanying drawings forming a part of this specification, in which similar characters of reference indicate corresponding parts in all the 40 views.

Figure 1 is a sectional side elevation of the means for carrying life lines; Fig. 2 is a sectional side elevation of another means for carrying a life line, part of the 45 gun or mortar being shown in elevation; Fig. 3 is a front end elevation of the same; and Fig. 4 is a rear end elevation of the projectile and the ring of the life line in expanded state.

50 The projectile A, shown in Fig. 1, is adapted to be fired out of a gun or mortar B by the use of a suitable explosive C, and in the base of the projectile A is formed a tapering recess A' for the reception of the 55 doubled-up end D' of a wire cord or cable D adapted to be fastened in the said recess

A' by being wedged by the use of lead E or other suitable material. The cord or cable D, after passing out of the recess A' extends along a recess A² formed in the base 60 of the projectile A to then extend along a groove A³ formed lengthwise in the peripheral face of the projectile A. The outer end of the wire cord or cable D terminates in a ring D² to which is attached one end of a 65 life line F of suitable length. When the projectile A is fired out of the gun or mortar B then the projectile after leaving the gun carries along the wire cord or cable D and the latter draws along the life line F. Now 70 it will be seen that by the use of the wire cord or cable D a flexible, strong and non-burnable connection is had between the projectile A and the life line F, and consequently the life line is carried safely to its 75 destination by the projectile A and the wire cord D. By having the cord D connected centrally with the base end of the projectile A the latter is not liable to tumble over during its flight, as the pull of the projectile A 80 on the wire cord D is centrally from the base of the projectile. It will also be noticed that by this arrangement the projectile A can be fired with great accuracy so as to insure the safe delivery of the line F to 85 ship or shore or other part.

The projectile G, shown in Fig. 2, is adapted to be fired out of a gun or mortar H provided with a suitable explosive charge C', and the projectile G is provided with a 90 recess G' open at the base and containing a coil of life line I, the forward end of which is preferably formed into a knot I' or doubled-up, and is wedged in a recess J² by the use of lead J or other material, the same 95 as above described in reference to the wire cord D. The rear end of the life line I terminates in a ring I² which is somewhat larger in diameter than the projectile G, but is pressed into the bore of the gun or mortar 100 K and rests on the base of the projectile G. One or a series of hooks K is attached to a split band L clamped on the muzzle end of the gun or mortar H, and the said hooks K are adapted to catch the ring I² when the 105 projectile G is fired and passes out of the gun or mortar H, it being understood that when the projectile G passes out of the gun and with it the ring I² then the latter expands by its own resiliency so as to readily 110 engage one or more of the hooks K. When the ring I² engages the hook or hooks K

then the life line I is drawn gradually out of the recess G' on the projectile G continuing its flight until it reaches its destination, and consequently the life line extends between the hooks K and the part reached by the projectile. It is understood that the points of the hooks K are out of the path of the projectile G, but are in close proximity thereto, so that the ring I² on expanding is readily caught by one or more of the hooks K at the time the projectile G is fired.

From the foregoing it will be seen that the life line F or I does not unduly hamper the projectile A or G in its flight, thus insuring a safe delivery of the life line at the desired destination.

Having thus described my invention, I claim as new and desire to secure by Letters Patent:

1. In means for carrying life lines, a projectile having a recess leading out through its base, and a life line coiled within the recess of the projectile and having one end secured in the bottom of the recess, and its other end terminating in a ring of greater diameter than the projectile and lying against the base of the projectile.

2. A means for carrying life lines, comprising a gun, a recessed projectile, a line within the recess of the projectile and having one end secured to said projectile, and means carried by the gun for catching the free end of the line on the projectile leaving the gun.

3. A means for carrying life lines, comprising a projectile provided with a recess open at the base of the projectile, a life line

coiled within the said recess and having one end anchored in the bottom of the recess, a ring in which terminates the other end of the said life line, and a firing gun for the said projectile and provided with a catching means for catching the said ring on the projectile leaving the firing gun.

4. A means for carrying life lines, comprising a projectile provided with a recess open at the base of the projectile, a life line coiled within the said recess and having one end anchored in the bottom of the recess, a ring on which terminates the other end of the said life line, a firing gun for the said projectile, and hooks in front of the muzzle of the gun and adapted to catch the said ring on the projectile leaving the gun.

5. A means for carrying life lines, comprising a projectile provided with a recess open at the base of the projectile, a life line coiled within the said recess and having one end anchored in the bottom of the recess, a ring on which terminates the other end of the said life line, a firing gun for the said projectile, hooks in front of the muzzle of the gun and adapted to catch the said ring on the projectile leaving the gun, and a band encircling the gun at the muzzle and carrying the said hooks.

In testimony whereof I have signed my name to this specification in the presence of two subscribing witnesses.

BENJAMIN F. McCREARY.
